(57) **CLAIM**

The ornamental design for a sensor module, as shown and described.

DESCRIPTION

FIG. 1 is a top isometric view of a sensor module according to our new design.

FIG. 2 is a bottom isometric view of the sensor module of FIG. 1.

FIG. 3 is a top plan view of the sensor module of FIG. 1.

FIG. 4 is a bottom plan view of the sensor module of FIG. 1.

FIG. 5 is a front plan view of the sensor module of FIG. 1.

FIG. 6 is a rear plan view of the sensor module of FIG. 1.

FIG. 7 is a first side plan view of the sensor module of FIG. 1.

FIG. 8 is a second side plan view of the sensor module of FIG. 1.

FIG. 9 is a top isometric view of a sensor module according to a second embodiment; and,

FIG. 10 is a bottom isometric view of the sensor module of FIG. 9.

The broken lines shown in the drawings depict portions of the sensor module that form no part of the claimed design.
